Primary Examiner — Rosemary K Tarcza*Assistant Examiner* — Christy Nemeth(74) *Attorney, Agent, or Firm* — Barnes & Thornburg LLP(57) **CLAIM**

The ornamental design for a foot rail for patient bed, as shown and described.

DESCRIPTION

FIG. 1 is a top front perspective view of a foot rail for patient bed showing our new design;

FIG. 2 is a front elevation view of the foot rail of FIG. 1; FIG. 3 is a rear elevation view of the foot rail of FIG. 1; FIG. 4 is an end elevation view of a first end of the foot rail of FIG. 1;

FIG. 5 is an end elevation view of a second end of the foot rail of FIG. 1;

FIG. 6 is a top plan view of the foot rail of FIG. 1; and, FIG. 7 is a bottom plan view of the foot rail of FIG. 1.

The broken lines shown in the figures depict environmental subject matter and form no part of the claimed design.

1 Claim, 3 Drawing Sheets# US D771,259 S
